MUFFLER

Walter H. Powers and Benton D. Jacokes, Jackson, Mich.,
assignors to Walker Manufacturing Company of Wisconsin,
Wisconsin, Racine, Wis., a corporation of Wisconsin

Application December 5, 1955, Serial No. 39,169

Term of patent 14 years

(Cl. D14—6)

Fig. 1 is a side elevation of a muffler showing our new design;

Fig. 2 is a section taken along the line 2—2 of Fig. 1;

Fig. 3 is a plan view of the muffler shown in Fig. 1;

Fig. 4 is an enlarged section taken along the line 4—4 of Fig. 3;

Fig. 5 is a perspective view; and

Fig. 6 is an end view taken from the right of Fig. 3.

The dominant feature of our design resides in the full line portion of the drawing.

We claim:

The ornamental design for a muffler, as shown and described.
